UNITED STATES PATENT OFFICE

148,933

DESIGN FOR AN ADJUSTABLE LINE
CONNECTOR

Edward H. Karleen, Morris Township, Morris County, N. J., assignor to Karleen, Incorporated, Morris Plains, N. J., a corporation of New Jersey

Application February 12, 1946, Serial No. 126,525

Term of patent 14 years

(Cl. D26—1)

To all whom it may concern:

Be it known that I, Edward H. Karleen, a citizen of the United States of America, residing in the township of Morris, in the county of Morris, State of New Jersey, have invented a new, original, and ornamental Design for an Adjustable Line Connector, of which the following is a specification, reference being had to the accompanying drawing, forming a part thereof, and on which:

Fig. 1 is a side perspective view of an adjustable line connector showing my new design; and

Fig. 2 is another perspective view thereof.

I claim:

The ornamental design for an adjustable line connector, as shown.

EDWARD H. KARLEEN.
